UNITED STATES PATENT OFFICE.

CHRISTIAN WILLIAM MEINECKE, OF JERSEY CITY, NEW JERSEY, AS-SIGNOR TO MEINECKE & CO., OF NEW YORK, N. Y., A CORPORA-TION OF NEW JERSEY.

DESIGN FOR A HOT-WATER-BAG CLOSURE.

SPECIFICATION forming part of Design No. 35,580, dated January 14, 1902.

Application filed October 11, 1901. Serial No. 78,389. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Hot-Water-Bag Closure, of which the following is a specification.

My invention relates to a new and original design for hot-water-bag closure and is illustrated in the accompanying drawings, in which—

15 The leading feature of my design resides in a closure having a beaded body and an annular flange, constituting a top for said body, said annular flange overhanging the body and being provided on its upper side with a handle, which handle has a portion above its lower part wider than such lower part and is ornamented by an encircling chain of smaller diameter than the wider portion of the handle.

In said drawings the letter a indicates the 25 body of the closure, having the beads b. An annular projecting flange or overhanging top is shown at d. The handle e is wider as it passes up or has a portion of greater width or diameter than its lower portion or the portion at the top d. A chain f encircles the handle, 30 and the widest part of the handle is greater than the diameter of the circularly-disposed chain, and this encircling chain or series of links surrounding the handle is the distinguishing feature of my design. 35

The design presents a hot-water-bag closure having a novel, pleasing, and distinguished appearance.

What I claim as new, and desire to secure by Letters Patent, is—

The design for a hot-water-bag closure substantially as herein shown and described.

In testimony whereof I have hereunto set my hand in the presence of two subscribing witnesses.

CHRISTIAN WILLIAM MEINECKE.
